UNITED STATES PATENT OFFICE.

FRED R. FICK, OF GALVA, IOWA.

SEPARATING GRATE FOR GRAIN THRASHERS.

Application filed February 5, 1923. Serial No. 616,997.

This invention relates to thrashing machines and particularly to a grate construction which is designed to afford a more efficient separation of the grain when being 5 thrashed.

The advantages thru which the results are obtained, as will be observed upon reference to the following specification, are due particularly to the arrangement of the separating bars, secondary to which is the manner in which the bars are arranged in grate sections, their manner of support, their individuality and the peculiar arrangement and construction of the rear grate sections 10 and the check plate associated therewith.

In the accompanying drawings which illustrate a preferred embodiment of my invention,

Figure 1 is a side elevation of the interior 20 of a thrashing machine, showing the manner of mounting the grate, and its relation to the thrashing cylinder;

Figure 2 is a top perspective view of the 25 grate removed from the machine;

Figure 3 is a front perspective view of the forward section, and

Figure 4 is a perspective view of the check plate.

In the present invention, the construction 30 distinguishes, principally from the prior art, in that the bars of the grate are arranged in the direction of travel of the cylinder instead of transversely thereof, which arrangement permits of and results in a more 35 efficient separation of the grain.

In the accompanying drawings I have shown generally at 2, the grate of a grain 40 thrashing machine, 4 illustrating a conventional form of cylinder, which in actual practice may be of any preferred or well known type and therefore requires no specific description. The structure to be described further in detail is supported in the thrashing machine frame in a manner to be 45 described.

The grate structure which also embodies the concaves at the forward part of the machine, comprises a forward concave 6, a plurality of adjoining grate sections 8 and 50 a rear upwardly inclined grate section 10. Each of these concave and grate sections is individual or independent and may be separably placed or removed when necessary.

As distinguished from prior construction

in which the separating bars are arranged 55 transversely of the direction of movement of the cylinder, each of the grate sections is rectangular in form and comprises a plurality of parallel longitudinal flat bars 9 set vertically in slotted transverse bars 12 which 60 are in turn supported upon transverse yokes 14, the upturned ends 16 of which are suitably mounted in the side members or plates of the thrashing machine frame.

The rearmost grate, which has been referred to as being upwardly and rearwardly inclined is constructed in a manner similar to the previously described sections and is backed by a sheet metal check plate 20 spaced therefrom and having forwardly extending wings which are suitably connected with said grate frame as shown.

By reference to Figure 1 of the drawing it will be seen that the upper edges of the inclined bars 10 lie in a plane spaced above the plane in which the upper edges of the cross bars lie and the lower edges of the inclined bars 10 are spaced above the inclined edges of the wings. This arrangement is such that there can be no return or rebound 75 blast of air and which will return trash or chaff to the incoming grain. The blast of air is deflected and passes over the inclined edges of the wings and between the wings and the bars and cannot rebound or return 80 to the volume of grain which is being deposited upon the upper surfaces of the edges of the inclined bars.

Having described my invention, what I claim as new is:

A grain check adapted to be used in conjunction with a thrasher cylinder and concave comprising a plate having a vertical intermediate portion and provided with side wings having inclined edges, spaced cross bars mounted upon the inclined edges of the wing and parallel spaced bars mounted upon the cross bars and inclined parallel with the inclined edges of the wings and having their lower edges spaced above the plane in which the inclined edges of the wings lie, the upper edges of the inclined bars lying in a plane spaced above the plane in which the upper edges of the cross bars lie.

In testimony whereof I affix my signature.

FRED R. FICK.
